UNITED STATES PATENT OFFICE.

FELIX J. McGUANE, OF CHICAGO, ILLINOIS.

BOWLING-BALL AND HANDLE.

No. 884,991.

Specification of Letters Patent.

Patented April 14, 1908.

Application filed January 26, 1907. Serial No. 354,199.

To all whom it may concern:

Be it known that I, FELIX J. McGUANE, a citizen of the United States, and a resident of Chicago, in the county of Cook and State 5 of Illinois, have invented new and Improved Bowling-Balls and Handles for Casting or Throwing Them, of which the following is a full, clear, and exact description.

This invention relates to the game of bowling, and has for its objects to provide a handle grip by which a bowling ball may be held conveniently by the player, the handle grip fitting the player's hand and being so constructed that it may be readily and in- 15stantly freed from the ball at the will of the player with sufficient momentum to carry it down the bowling alley.

Another object of the invention is to provide a bowling ball so constructed that it will 20 fit the handle grip by which it may be temporarily held.

The specification and drawings which accompany my application, disclose one embodiment of my invention, the scope of which 25 however is not limited thereto, but is set forth in the appended claims.

Reference is to be had to the accompanying drawings forming a part of this specification, in which similar characters of reference 30 indicate corresponding parts in all the figures, in which.

Figure 1 is a sectional side elevation of the handle or gun, showing the stem thereof inserted in the ball without being locked thereto; Fig. 2 is a sectional side elevation of Fig. 35 1, showing the pivotal keys of the stem of the handle or gun thrown out preparatory to locking the ball to the handle or gun; Fig. 3 is a sectional plan view of the stem of the gun 40 or handle on the line 3—3 of Fig. 2; and Fig. 4 is a sectional view of the central portion of a bowling ball showing a modified construction on a smaller scale.

The handle grip 1 has a pistol grip with 45 finger holes 2, which is made to fit the hand of the player. It is preferable to fill the frame 4 of the grip with cork or other suitable material 5 which may be secured thereto in the manner usual in the manufacture of 50 pistol grips. Projecting from the grip is a stem piece 3 at the center of the inner terminal of which is a boss 6. The stem piece 3 is bored from the outer terminal inwardly to form the cylindrical hole 7 which extends to 55 a point in close proximity to the boss 6 at the inner terminal of the stem. A cylindrical

hole 8 smaller in diameter than the hole 7 but with the same axis is bored from the inner terminal of the hole 7 through the remainder of the stem 3 and the boss 6. Four 60 slots 9, each at right angles to each of the adjoining ones and all longitudinal of the stem, are cut in the outer terminal in the stem through to the cylindrical hole 7. An annular groove 10 is cut around the stem 3 in- 65 termediate of the terminals of the slots 9 but nearer the inner terminal. A rod 11 ex- 70 tends through the hole of the stem piece 3 the said rod having a spreader 12 at the outer terminal and a screw thread at the inner terminal. The rod 11 is turned to fit the cylindrical hole 7 from the spreader 12 for the greater part of its length, the other 75 terminal of the rod being turned to fit the smaller hole 8 and to permit a spiral spring 13 to be introduced around the rod between the abutments formed by the inner terminal 14 of the larger hole 7 and inner terminal 15 of the greater diameter of the rod 11. At a 80 point near the inner terminal of the larger diameter of the rod 11 is turned a shoulder 16. On the outside of the stem piece near the grip is a thumb lever 28 pivoted at 17, at the terminal of one arm of which is pivoted a bolt 18, and on the other arm is a 85 thumb piece. The bolt 18 is adapted to fit through an opening the stem against the shoulder 16 of the rod 11 and the leaf spring 19 on the thumb lever is adapted to hold it in this position until pressure is brought to 90 bear on the thumb piece on the lever 16. In each of the four slots 9 is inserted a pivoted key 20 the said keys having as bearings a wire or ring 21 passing around the rod in the groove 10. Leaf springs 22 hold the pivotal 95 keys 20 snug against the rod 11 without exposing any part thereof without the periphery of the stem piece. The outer terminals of the keys are curved inwardly with notches 23 at the termination of the curves 100 so that they may be readily diverged by the spreader 12 and be retained in that position by the notches 23, fitting the spreader. When the rod 11 is introduced in the hole of the stem piece the spring 13 having been ad- 105 justed thereon a nut is screwed on its inner terminal. A longitudinal key 29 is inserted in a groove in the front of the stem piece and projects beyond its surface.

The bowling ball which I propose to use in 110 connection with my handle or gun is constructed as follows: The ball 24 has a hole

bored therein in which is inserted a lining or bushing 25. The head of the lining of the hole in the ball, which is preferably made separate from the cylindrical portion, has 5 an outwardly projecting portion 26 which is axially alined with the axis of the hole in the ball. The cylindrical lining of the hole in the ball a short distance from the inner portions converges, being frusto-conical in 10 shape, until it meets the stem of the grip when it continues of that diameter for the remainder of its length. The lining or bushing does not extend to the surface of the ball nor is it of a diameter as great as that of the 15 hole in the ball for some distance from its outer terminal. In this space between the lining or bushing and the ball is inserted a fiber or other material 30, which extends to the surface of the ball and conforms therewith. The fiber or similar material 30 is 20 introduced to prevent any of the metal parts of the lining or bushing from coming into contact with the bowling alley or pins when the ball is being used. A groove 27 is made 25 in the lining of the ball to fit the key 29 of the stem of the grip.

In Fig. 4 I have shown a modified construction of the bowling ball, in which it is unnecessary to use the fiber 30 to keep the 30 bushing 25 from coming into contact with the pins or alley. In this construction, a hole 31 is bored nearly through the ball, the hole being tapered with a counterbore and the remainder of the ball being bored 35 through to form a hole 32 of less diameter than the hole passing nearly through the ball, the different diameters of the hole being joined by the tapered portion 33. The bushing 25^a is then driven through the ball up 40 against the tapered portion 33, and a wooden plug 34, having a screw or projection 26^a on its inner end, is driven into the ball up against the bushing, and its outer end is rounded off to conform to the contour of the 45 ball. As the neck of the bushing is not long enough to reach the surface of the ball, no part of the bushing can come into contact with the bowling alley or pins.

In using my invention, the stem of the 50 grip is introduced in the hole in the ball and is pressed downwardly so that the spreader 12 will come in contact with the projecting member 26 and will prevent the rod 11 from going further, while the stem piece may be 55 pushed in further until the pivotal keys 20 are pressed outwardly by the spreader 12, the notches 23 fitting the spreader and the bob 18 springing into active position against the shoulder 16. If the grip is now lifted it 60 will be found that the pivotal keys 20 abut against the frusto-conical surface of the lining or bushing and that the bowling ball is locked to the grip. The player may now 65 take a position on the bowling alley and, holding the grip in his hand with his thumb

against the thumb-piece on the thumb-lever 16, swing the ball or run with it and when he wishes push the thumb-piece, when the rod, being freed from the bolt, will be pushed by the spring so that the spreader thereon will 70 be freed from the keys, which will be drawn within the slots by the leaf springs and the ball will be free to travel in the direction indicated by the preliminary movements of the player in obtaining momentum therefor. 75

Having thus described my invention I claim as new and desire to secure by Letters Patent:

1. An article of manufacture, consisting of a bowling ball having a hole therein, a grip 80 device provided with a rigid stem adapted to be inserted in the hole, a key for locking the stem in the hole, and means in connection with the stem and the hole for moving the key into locking position.

2. An article of manufacture, consisting of a bowling ball having a hole therein, said hole increasing in diameter towards its bottom, a grip device having a rigid stem adapted to be inserted into the hole, a key for locking the stem in the hole, and means in connection with the stem and the hole for moving the key into locking position.

3. An article of manufacture, consisting of a bowling ball having a hole therein, said 95 hole increasing in diameter toward its bottom, a grip device provided with a rigid stem adapted to be inserted into the hole, a key pivoted to the stem, a spring for normally holding the key against the stem, and means 100 in connection with the stem and the hole for moving the key outwardly to lock the stem in the hole.

4. An article of manufacture, consisting of a bowling ball having a hole therein, a grip 105 device having a rigid stem adapted to be inserted into the hole, a longitudinal slot in the stem extending a distance from its inner terminal, a key pivoted in the slot for locking the stem in the hole, and means in connection with the stem and the hole for moving the key into locking position.

5. An article of manufacture consisting of a bowling ball having a hole therein, a grip device with a stem adapted to fit the said 115 hole in the ball, a longitudinal slot in the stem extending a distance from its inner terminal, an annular groove on the periphery of the stem which cuts the said slot, a key fitting the said slot, which is pivoted by a ring 120 passing around the said groove, means to hold the said key normally within the perpendicular plane of the said slot and means to extend it outwardly.

6. An article of manufacture, consisting of 125 a bowling ball having a hole therein, a grip device having a hollow rigid stem adapted to be inserted in the hole, said stem having a longitudinal slot extending a distance from its inner terminal, a key pivoted at one end 130

within the slot, for locking the stem within the hole, a rod passing through the stem and provided with a spreader for engaging the key, whereby to move said key into locking position, and means within the hole for moving the spreader.

7. An article of manufacture consisting of a bowling ball having a hole therein, a grip device with a stem adapted to be inserted in the said hole in the ball, a longitudinal slot in the stem extending a distance from its inner terminal, a key pivoted within the slot, a rod disposed longitudinally of the stem, a spreader on the inner terminal of rod, and means to bring the spreader into engagement with the free terminal of the key at the bottom of the hole in the ball.

8. An article of manufacture, comprising a bowling ball having a hole therein, said hole increasing in diameter towards its bottom, a grip device having a rigid stem adapted to be inserted into the hole, a key pivoted to the stem to engage the wall of the hole to lock the grip device to the ball, a rod within the stem, and provided with a spreader for moving the key into locking position, and means within the hole for moving the rod to operate the spreader.

9. An article of manufacture consisting of a bowling ball having a hole therein, a grip device with a stem rigidly secured thereto and adapted to be inserted into the hole in the ball, a key pivoted to the stem, a rod disposed within the stem, a spreader on the inner terminal of the rod, and means to hold the rod yieldingly with the spreader away from the key.

10. An article of manufacture, consisting of a bowling ball having a hole therein, a grip device having a hollow stem adapted to be inserted within the hole, a key pivoted to the stem and adapted to lock the grip device to the ball, a rod arranged longitudinally within the stem, and provided with a spreader for engaging the key to move the same into locking position, means within the hole for moving the rod to operate the spreader, and a spring acting on the rod to return the spreader to its original position.

50 11. An article of manufacture, consisting of a bowling ball having a hole therein, a grip device provided with a hollow stem adapted to be inserted into the hole, a key pivoted to the stem for locking the same to the ball, a rod movable within the stem, a spreader on the rod for engaging the key, whereby to move it into locking position, a spring acting on the rod to normally retain the spreader in inoperative position, a shoulder on the rod, means in connection with the ball and within the hole for moving the rod to move the spreader into operative position, and a bolt for engaging the shoulder on the rod to hold said rod with the spreader in operative position.

12. An article of manufacture, consisting of a bowling ball having a hole therein, a grip device provided with a rigid hollow stem adapted to be inserted into the hole, a longitudinal slot in the stem extending a distance from its inner terminal, a key pivoted within the slot and adapted to engage the wall of the hole for locking the stem to the ball, a rod movable within the stem, said rod being provided with a spreader for moving the key into locking position, a spring acting on the rod to normally maintain the spreader in inoperative position, means in connection with the ball and within the hole for moving the rod, whereby to bring the spreader into operative position, and means engaging the rod for retaining it in such position.

13. An article of manufacture, consisting of a bowling ball having a hole therein, a grip device having a hollow stem adapted to be inserted in the hole, a key pivoted to the stem and adapted to engage the wall of the hole to lock the ball and the stem together, a rod movable within the stem, and provided with a spreader for engaging the key to move it into locking position, said key being provided with a notch for engagement by the spreader, a spring acting on the rod to move the spreader out of operative position, means in the hole in connection with the ball for moving the rod to bring the spreader into operative position, and means engaging the rod for retaining the spreader in such position.

14. An article of manufacture consisting of a bowling ball having a hole therein, a longitudinal groove in the said hole, a grip having a stem with a longitudinal key adapted to fit the said groove, a key pivoted to the stem, means to hold the pivoted key close to the stem, and means to extend it outwardly.

15. An article of manufacture consisting of a bowling ball having a hole therein, a bushing within the said hole, the said bushing being frusto-conical in shape for a portion of its length, a grip device having a stem rigidly secured thereto and adapted to be inserted into said hole, a key pivoted to the said stem, means to hold the key close to the stem, and means to extend it outwardly.

16. An article of manufacture consisting of a bowling ball having a hole therein, a bushing within the said hole, the said bushing being frusto-conical in shape for a portion of its length, a fiber-like material extending from the frusto-conical portion of the bushing to the ball and to the surface of the ball to conform therewith, a grip device having a stem adapted to be inserted into the hole in the ball, a key pivoted to the stem, means to hold the key close to the stem, and means to extend it outwardly.

17. An article of manufacture consisting of a bowling ball having a hole therein, a bushing within the said hole in the ball, the

said bushing being frusto-conical in shape for a portion of its length, a projecting member at the bottom of the bushing, a grip having a hollow stem adapted to be inserted into 5 the hole in the ball, a key pivoted to the stem, a rod disposed within the stem, a spreader on the inner terminal of the rod, a notch in the free terminal of the key adapted to engage with the spreader, and means to hold yield- 10 ingly the rod extended within the stem.

18. An article of manufacture consisting of a bowling ball having a hole therein, a bushing within the said hole in the ball, the said bushing being frusto-conical in shape for 15 a portion of its length, a grip device having a hollow stem adapted to be inserted into the hole in the ball, a key pivoted to the stem, a rod disposed within the stem, a spreader on the inner terminal of the rod, the free terminal of the key having a notch adapted to engage the spreader, means to hold the rod ex- 20 tended away from the handle of the grip, means for extending the rod toward the handle of the grip, a shoulder on the rod, a bolt 25 passing through the stem, which is adapted to engage the shoulder of the rod and hold the rod partially withdrawn from the stem, and a thumb lever on the outside of the stem controlling the bolt.

30 19. An article of manufacture consisting of a bowling ball having a hole therein, a bushing in the hole in the ball, the bushing being frusto-conical in shape for a portion of its length, a longitudinal groove in the bush- 35 ing extending a distance from its outer terminal, a projecting surface at the center of the head of the bushing, a grip device having a stem for insertion in the hole, and means in connection with the stem for engaging the 40 wall of the hole to lock the grip device to the ball.

20. An article of manufacture consisting of a bowling ball, having a hole therein, a bushing in the said hole, the outer and inner 45 terminals of the bushing being of different diameters with a frusto-conical intervening portion and a grip device provided with a stem for insertion in the hole, said stem hav- 50 ing means for engaging the frusto-conical portion for locking the grip device to the ball.

21. An article of manufacture, consisting of a bowling ball having a hole therein, a bushing in the hole, said bushing being of lesser thickness toward the bottom of the hole, whereby to form a frusto-conical wall 55 for the hole, said hole being of greater depth than the length of the bushing, a fiber-like material between the outer portion of the bushing and the ball and extending to the surface thereof, and a grip device provided with a stem for entering the hole, said stem having means for engaging the frusto-conical wall whereby to lock the parts together. 60

22. The combination with the bowling ball having a hole therein, of a grip device comprising a rigid stem adapted for insertion into the hole, a key pivoted to the stem for engaging the wall of the hole to lock the stem thereto, means for moving said key into locking position, and means within the hole for 70 operating said moving means.

23. The combination with the bowling ball, having a hole therein, of a grip device provided with a rigid stem for insertion into the hole, a key pivoted to the stem and adapted 75 to engage the wall of the hole to lock the grip device thereto, yielding means for normally holding the key in inoperative position, means for moving the key into operative position, and means within the hole for operat- 80 ing said moving means.

24. The combination with the bowling ball having a hole therein, of a grip device having a rigid stem for insertion in the hole, said stem having a longitudinal slot in the terminal thereof, a key pivoted in the slot and adapted to engage the wall of the hole to lock the grip device thereto, a spring normally holding the key out of operative position, means for moving the key into operative position, and means within the hole for operating said moving means. 85 90

In testimony whereof I have signed my name to this specification in the presence of two subscribing witnesses.
